[57] CLAIM

The ornamental design for golf cart drink caddy, as shown and described.

DESCRIPTION

FIG. 1 is a front elevational view of a golf cart drink caddy, showing my new design;

FIG. 2 is a top plan view thereof;

FIG. 3 is a bottom plan view thereof;

FIG. 4 is a rear elevational view thereof;

FIG. 5 is a side view thereof, the view of the opposite side being a mirror image thereof; and,

FIG. 6 is a perspective view of the golf cart drink caddy with a drink container and portion of a golf cart shaft illustrated in broken lines and forming no part of the invention.
